A. LINNEMANN

MECHANICAL COAL AND ROCK MINING MACHINE

Filed July 29, 1924

Inventor:

Adolf Linnemann
By: Helen S. R.
Atty

Patented Nov. 4, 1924.

UNITED STATES PATENT OFFICE.

ADOLF LINNEMANN, OF BERLIN, GERMANY.

MECHANICAL COAL AND ROCK MINING MACHINE.

Application filed July 29, 1924. Serial No. 728,927.

To all whom it may concern:

Be it known that I, ADOLF LINNEMANN, a citizen of the German Republic, residing at Berlin, Germany, Scharnhorststr 9, have invented certain new and useful Improvements in Mechanical Coal and Rock Mining Machine (for which I have filed an application in Germany on Feb. 10, 1923), of which the following is a specification.

10 The object of this invention is to provide improved means for mining coal and rock.

A further object of this invention is to provide improved means for breaking portions of coal off the face of a vein or portions of rock off the solid rock.

15 The invention relates to a mechanical contrivance adapted to obtain this object in deep level mining as well as in surface or open working without the use of explosives and similar materials.

20 In the drawing accompanying this application and forming part thereof, a modification embodying the principle of my invention has been illustrated by way of example, 25 the illustration disclosing a longitudinal sectional view of the tool.

In the construction of the machine or tool as shown, the character (a) is denoting a tube, preferably made from a material of 20 great resisting strength, such as steel; fixed to the back-end of this tube, so as to form an integral part of same, is a nut (b), in which a threaded spindle or feed bar (c) may be screwed forward and backward, for instance 25 by means of a spanner, hand-wheel or the like, which may be placed upon the end of threaded feed bar (c) projecting from the back end of the tube (a). Inserted and guided in the fore portion of the tube (a) is 30 a rod (e) and a pressure plate or step-block (f) is provided at the front end of rod (e).

The middle portion of the rod (e) is formed to wedge shape, and this wedge-shaped portion, when the rod (e) is being 45 pushed ahead in the tube (a), is taking effect against the inner faces of the wedge-shaped jaws (g), pressing and pushing out the jaws through suitable apertures in the tube (a) in correspondence to the taper of 50 the wedge-shaped portion of the shaft (e).

The rod (e) is being pushed ahead within the tube (a) by the forward movement of the feed bar (c) caused by turning the spanner or hand-wheel at its back-end.

55 In order to facilitate the rotary operation

of the feed bar (c) and the rod (e). It is, however, quite possible also, to make the feed bar (c) act directly on the rod (e).

The operation of the tool in practical use takes place in the manner described in the 60 following:

A hole is being bored into the coal or rock, said hole having a free width corresponding to the outside diameter of the tube (a). The jaws (g) are in alignment with the outside 65 surface of the tube (a), so that the tool is adapted to be inserted into the hole drilled into the coal or rock. As soon as the thrust-plate or step-block (f) is abutting against the bottom of the drill hole, and the feed 70 bar (c) is being screwed further into the nut (b), the wedge-shaped portion of the rod (e) is pushing and forcing the jaws (g) outward, so that the cutting edges of the jaws 75 (g) will enter and penetrate into the coal or rock surrounding the tube (a). During this operation the single layers of the coal or rock will crack and break up. The feed bar (c) is now being rotated further in the same 80 sense, and through this action the tube (a) is being moved backward in the drilled hole, and, at the same time, the jaws (g), penetrated into the coal or the rock, will catch 85 and tear along with themselves towards the entrance of the drill hole the split-off coal or rock, so that the latter may be cleared away after the removal of the coal breaking tool.

In the case under consideration it is not necessary to pick or cut the coal in the region surrounding the drill hole. The coal is being 90 cracked, therefore, entirely without picking or cutting.

Instead of having a wedge-shaped portion provided at the rod (e) for pushing the jaws (g), a suitable lever-action may be arranged intermediate the rod (e) and the jaws (g), without affecting in any way the principle of the present invention.

I claim:

1. In a coal- and rock-mining machine, the combination with a tube adapted to be inserted into a hole drilled into the coal and jaws operatively arranged in the further portion of said tube, said jaws adapted to penetrate into the surrounding coal or rock, of a nut integrally fixed to said tube, a feed bar, a rod and a step-block, substantially as set forth.

2. In a coal- and rock-mining machine, the combination with a tube adapted to be in-

- 5 inserted into a hole drilled into the coal and
10 jaws operatively arranged in the further
portion of said tube, said jaws adapted to
penetrate into the surrounding coal, of a nut
15 integrally fixed to said tube, said tube apertured
20 to permit the passage of said jaws, a
threaded feed bar, a rod and a step-block,
substantially as set forth.
3. In a coal- and rock-mining machine, the
10 combination with a tube, jaws arranged in
the fore-portion of said tube and adapted
15 to penetrate into the surrounding coal or
rock, of a nut integrally fixed to said tube,
20 said tube apertured so as to permit the pas-
sage of the said jaws, a threaded feed-bar
25 adapted to screw forward and backward in
said nut, a rod arranged in front of said
feed bar within said tube and adapted to
30 slide within said tube with the forward
movement of said feed bar, and a step-block,
substantially as set forth.
4. In a coal- and rock-mining machine,
10 the combination with a tube and jaws ar-
ranged in the fore-portion of said tube, of a
15 nut integrally fixed to said tube, said tube
apertured to take said jaws, a threaded feed
20 bar adapted to screw in said nut, a rod
adapted to be moved ahead by said feed bar
25 within said tube, the middle section of said
rod shaped to form a wedge-portion, the taper
30 of said wedge-portion running forward,
and a step-block, substantially as set forth.
5. In a coal- and rock-mining machine,
10 the combination with a tube, and jaws ar-
ranged in the fore-portion of said tube, of
15 a nut integrally fixed to the said tube, said
tube apertured to take said jaws, a threaded
20 feed bar adapted to screw in said nut, and
a rod adapted to be moved forward by said
25 feed bar within said tube, the middle portion
30 of said rod shaped to form a wedge
portion, the taper of said wedge-portion running
forward, the inclined surfaces of
35 said tapering wedge-portion in engagement
40 with the back-faces of said jaws, the wedge-
portion thereby adapted to drive the said
45 jaws radially into the rock, substantially
50 as set forth.
6. In a coal- and rock-mining machine,
50 the combination with a tube, and jaws ar-
ranged in the fore-portion of said tube and
adapted to penetrate into the surrounding
55 coal or rock, of a nut integrally fixed to
said tube, said tube apertured so as to per-
mit the passage of the said jaws, a threaded
feed-bar adapted to screw forward and
60 backward in said nut, a rod arranged in
front of said feed bar within said tube
and adapted to slide within said tube with
the forward movement of said feed bar, and
65 a step-block arranged at the forward end
of the said rod, said step-block adapted to
rest against the bottom of the hole drilled
into the coal or rock, substantially as set
forth.
7. In a coal- and rock-mining machine,
70 the combination with a tube, and jaws ar-
ranged in the fore-portion of said tube and
adapted to penetrate into the surrounding
75 coal or rock, of a nut integrally fixed to
said tube, said tube apertured so as to per-
mit the passage of the said jaws, a threaded
feed-bar adapted to screw forward and
80 backward in said nut, a rod arranged in
front of said feed bar within said tube
and adapted to slide within said tube with
the forward movement of said feed bar, and
85 a step-block arranged at the forward end
of the said rod, said step-block adapted to
rest against the bottom of the hole drilled
into the coal or rock, the said jaws, in their
90 extended position, adapted to catch and
tear along with them toward the entrance
of the drill-hole the split-off coal or rock
as soon as the feed-bar is being turned on
95 in the same sense after the step-block is in
engagement with the bottom of the bore-
hole, substantially as set forth.
8. In a coal- and rock-mining machine,
90 the combination with a tube, jaws arranged
in the fore-portion of said tube and adapt-
ed to penetrate into the surrounding coal or
95 rock, of a nut integrally fixed to said tube,
said tube apertured so as to permit the pas-
sage of the said jaws, a threaded feed-bar
100 adapted to screw forward and backward in
said nut, a rod arranged in front of said
feed bar within said tube and adapted to
105 slide within said tube with the forward
movement of said feed bar, and a lever han-
dle fitted to the back extremity of said feed
110 bar and adapted to rotate the said feed bar,
115 substantially as set forth.
9. In a coal- and rock-mining machine
105 the combination with a tube, jaws arranged
in the fore-portion of said tube and adapted
110 to penetrate into the surrounding coal or
rock, of a nut integrally fixed to said tube,
115 said tube apertured so as to permit the pas-
sage of the said jaws, a threaded feed-bar
120 adapted to screw forward and backward in
said nut, a rod arranged in front of said
feed bar within said tube and adapted to
125 slide within said tube with the forward
movement of said feed bar, and a hand-
wheel fitted to the back extremity of said
feed bar and adapted to rotate the said feed
130 bar, substantially as set forth.
10. In a coal- and rock-mining machine,
120 the combination with a tube, jaws arranged
in the fore-portion of said tube and adapted
125 to penetrate into the surrounding coal or
rock, of a nut integrally fixed to said tube,
130 said tube apertured so as to permit the pas-
sage of the said jaws, a threaded feed-bar
135 adapted to screw forward and backward in
said nut, a rod arranged in front of said
feed bar within said tube and adapted to
140 slide within said tube with the forward
movement of said feed bar, and a lever

arrangement attached to the said rod and adapted to push the said jaws radially outward, substantially as set forth.

11. In a coal- and rock-mining machine, 5 the combination with a tube, jaws arranged in the fore-portion of said tube and adapted to penetrate into the surrounding coal or rock, of a nut integrally fixed to said tube, said tube apertured so as to permit the passage 10 of the said jaws, a threaded feed-bar adapted to screw forward and backward in said nut, a rod arranged in front of said

feed bar within said tube and adapted to slide within said tube with the forward movement of the said feed bar, a step block, 15 and a friction-reducing device positioned intermediate the said feed bar and the said rod, substantially as set forth.

In testimony whereof I affix my signature in presence of two witnesses.

ADOLF LINNEMANN.
